UNITED STATES PATENT OFFICE.

LOUIS H. OTTO, OF CEDAR MILLS, MINNESOTA.

Brake for Phonographs.

1,106,237.

Specification of Letters Patent. Patented Aug. 4, 1914.

Application filed May 13, 1911. Serial No. 626,888.

To all whom it may concern:

Be it known that I, Louis H. Otto, a citizen of the United States, residing at Cedar Mills, in the county of Meeker and State of Minnesota, have invented new and useful Improvements in Brakes for Phonographs, of which the following is a specification.

An object of the invention is to provide a brake for phonographs, for automatically stopping the operation of the phonograph when the reproducer needle has reached the end of the record.

My device is adaptable for phonographs using either disk or cylinder records and embodies among other features means for engagement with the controlling lever and the reproducing arm of the machine, whereby the lever will be actuated to stop the operation of the machine when the needle attached to the reproducer of the reproducer arm has reached the end of the record.

For the purpose mentioned, use is made of a rod connected at one end to the reproducer arm of the machine, a sleeve pivotally connected to the other end of the said rod, and a second rod adjustably mounted in the said sleeve, the said second rod being adapted to engage the controlling means of the phonograph.

Reference is to be had to the accompanying drawings constituting a part of this specification, in which similar characters of reference denote corresponding parts in all the views, and in which—

Figure 1 is a perspective view of a phonograph showing my device attached thereto, parts being broken away to disclose the underlying structure. Fig. 2 is a plan view of a phonograph record showing a groove provided on the upper surface thereof and adapted to receive the needle of the phonograph therein.

Referring more particularly to the views, I provide a rod 10 having a clamp 11 formed at one end thereof for connection with a reproducer arm 12 of a phonograph 13 and pivotally mounted on the other end of the rod 10 is a sleeve 14, the other end of the said sleeve being connected to a chain 15 and adapted to slidably receive therein a rod 16. The other end of the rod 16 is connected to a controlling lever 19 of the phonograph 13 and has an end of the chain 15 connected thereto. A record 20 having the usual sound producing lines formed thereon is adapted to be disposed on the phonograph

in the usual manner and the said record is provided with a groove 21, formed at the inner end of the sound producing lines as shown in Fig. 1. The usual sound reproducing needle 22 is attached to a reproducer 23 secured to the arm 12 and when the said needle 22 is moved to operate over the sound producing lines of the record 20 it is adapted to be received in the groove 21 as will be hereinafter more fully disclosed.

In the operation of the device described, the arm 12 when in normal position will be arranged so that the needle 22 will lie adjacent the outer edge of the record 20 so that when the record is rotated, the needle will be advanced over the sound producing lines toward the inner portion or nucleus of the record, it being understood that the controlling lever 19 must be disengaged from the usual disk supporting the record and which imparts rotation thereto in order that the disk can rotate and impart rotation to the record so that the arm 12 will swing toward the center of the record as the needle is advanced over the sound producing lines. Now it will be seen that when the arm 12 swings inwardly the rod 10 will swing rearwardly, the said rod being rigid with the arm and, in consequence thereof, a pull will be exerted on the sleeve 14 which, connected to the rod 16 by the chain 15, will impart a pull on the rod 16 when the chain 15 becomes taut, the chain 15 being so adjusted with respect to the sleeve 14 and rod 16 that at the moment the needle reaches the end of the sound producing lines on the record, the pull on the rod 16 will be sufficient to actuate the controlling lever 19 and stop the rotation of the record. It will, therefore, be seen that the length of the chain 15 can be readily adjusted and will assume its maximum tension when the needle 22 reaches the inner end of the sound producing lines of the record, and it will be further understood that the outward sliding movement of the sleeve relatively to the rod will result in the chain becoming taut to exert the required pull on the rod 16.

From the foregoing description it will be seen that a device is provided for automatically stopping the rotation of a record when the needle has reached the inner end thereof and it will be further seen that a suitable adjustment of my device can be accomplished so that the same can be used in connection with various sized records.

My device can be employed in connection with both cylindrical or disk records and can be conveniently attached to any phonograph.

5 Having thus fully described the invention, what I claim as new, is:—

1. In combination with a base, a member mounted to swing thereon and a second member revolute thereon, the swinging member being adapted to operate over the revolute member, and a stop lever for stopping the rotation of the revolute member, a rod having pivotal connection with the said stop lever, a sleeve slidably receiving 10 the free end of the rod, a second rod rigid on the swinging member and extending at right angles thereto, with the free end of the second rod having pivotal connection with the said sleeve, and means connecting 15 the first mentioned rod with the second mentioned rod for imparting a pull on the first mentioned rod to actuate the said stop lever and stop the rotation of the said revolute member when the said swinging member 20 reaches the center of the said revolute member, the advancement of the said rod with the said swinging member being adapted to exert a pull on the said sleeve to actuate the first mentioned rod through the me- 25

dium of the said connecting means and actuate the said stop lever, the relative outward sliding movement of the first mentioned rod and sleeve being limited by the said means.

2. In combination with a base, a member mounted to swing thereon and a second member revolute thereon, the swinging member being adapted to operate over the revolute member, and a stop lever for controlling the rotation of the revolute member, of a rod having pivotal connection with the said stop lever, a sleeve having slidable connection with the said rod, a second rod rigid on the swinging member and having pivotal connection with the said sleeve, and a chain having connection with the first mentioned rod and with the said sleeve for limiting the sliding movement of the sleeve relatively to the said first mentioned rod, the length of the said chain being adapted to be increased or decreased for holding the 40 said sleeve rigid relatively to the said position when the said chain is in tension.

In testimony whereof I affix my signature in presence of two witnesses.

LOUIS H. OTTO.
